UNITED STATES PATENT OFFICE.

CARL S. NORDEN, OF WAKEFIELD, MASSACHUSETTS, ASSIGNOR TO UNITED SHOE MACHINERY COMPANY, OF PATERSON, NEW JERSEY, A CORPORATION OF NEW JERSEY.

MACHINE FOR IMPARTING FLEXIBILITY TO THE SOLES OF BOOTS AND SHOES.

1,150,143.

Specification of Letters Patent.

Patented Aug. 17, 1915.

Application filed November 11, 1911. Serial No. 659,701.

To all whom it may concern:

Be it known that I, CARL S. NORDEN, a subject of the King of Sweden, residing at Wakefield, in the county of Middlesex and 5 State of Massachusetts, have invented certain Improvements in Machines for Imparting Flexibility to the Soles of Boots and Shoes, of which the following description, in connection with the accompanying drawings, 10 is a specification, like reference characters on the drawings indicating like parts in the several figures.

This invention relates to a machine for increasing the flexibility of a piece of stock 15 and is herein illustrated as embodied in a machine for imparting flexibility to the sole of a shoe.

A sole before it is attached to the upper of a shoe has a certain stiffness, and an additional stiffness is imparted to it by the operations performed upon it during said attachment. The soles of boots and shoes are, therefore, often to a noticeable and objectionable degree stiff and unyielding so 25 that a certain amount of discomfort is caused the wearer until the boot or shoe has been subjected to considerable wear.

The general object of the present invention is to remove as completely as possible 30 the stiffness caused by the stitching, leveling and other operations and to impart an additional flexibility to the sole. And to this end one feature of the invention consists in the provision in a machine of the 35 class described of a support for a shoe and means for progressively flexing the sole of said shoe. Any suitable means for accomplishing this result may be made use of, and in the illustrated embodiment an undulation is produced in the sole, said undulation being caused to travel along the 40 sole throughout that portion of the sole to which flexibility is to be imparted.

Inasmuch as the upper of the shoe comprises certain parts to which a permanent 45 stiffness is intentionally imparted, it is desirable that means be provided to prevent such parts from being crumpled or broken during the flexing of the sole; and another 50 feature of the invention consists in the provision of such means. In the illustrated embodiment this takes the form of a toe piece which is automatically held in the toe of the shoe and thereby prevents injury

to the box toe during the operation upon 55 the sole.

These and other features of the invention including certain details of construction and combinations of parts will be described in connection with an illustrative machine 60 and pointed out in the appended claims.

Referring to the accompanying drawings, Figure 1 is a perspective of a machine in which the present invention is embodied; Fig. 2 is a plan of the shoe support showing the position it occupies in the shoe; and Fig. 3 is an elevation of the shoe support and the coöperating rollers, the sole of the shoe being shown in full lines in the position which it occupies before pressure is applied, 70 and in dotted lines after the undulation or wave has been produced.

The frame of the machine comprises a base 1, a standard 3, a platform 5, an arch 7 and two upright coöperating guides 9 75 and 11. Mounted in bearings supported on the platform 5 are rollers 13 herein shown as having a concave contour from end to end, said rollers being spaced so as to permit the sole of the shoe to be forced down between them in a manner presently to be described. Slidably mounted on the cylindrical guide 9 and held from angular movement by contact with the flat face of the guide 11 is a bracket 15 normally held in 80 raised position by a spring 17 and arranged to be depressed by a treadle 19 through the following connections. The treadle 19 is carried at the end of a rod 21 which is pivoted to the standard of the machine at 23 90 and is connected by a link 25 with an arm 27, also pivoted to the standard at 29, said arm being normally held in raised position by means of a spring. Pivoted to the free end of the arm 27 at 33 is a yoke having attached to it a rod 35, said rod at its upper end being attached to a cross bar 37. This cross bar at its extremities carries rods 39 which at their upper ends are connected with a second cross bar 41, carried by the 100 sliding bracket 15. It will now be apparent that the bracket 15 and treadle 19 are normally held in raised position and that depression of the treadle causes depression of the bracket 15.

The outer end of the bracket 15 is provided with a bearing 42 in which is mounted the reduced end 43 of the arm 45 of the

shoe support, said arm being provided with a shoulder which abuts the flat under side of the enlargement 47 on the lower end of the bearing, and being held in place by a 5 cotter pin 49. A pin 51 set into the reduced end 43 of the arm 45 extends through a slot 53 in the bearing 42 and limits the angular movement of the arm 45. Attached to the lower end of the arm 45 by means of a flexible 10 and extensible connection, herein shown as a coiled spring 55, is a toe-piece 57, the spring in the illustrative construction having one end coiled about a pin or projection 59 on the arm 45 and having the other end 15 fastened in any suitable manner to the toe-piece.

It is desirable that the box-toe of the shoe be adequately supported and that at the same time the proper flexing of the sole be 20 permitted. For this reason, a toe-piece having resiliency is preferable, and in the illustrative machine the toe-piece is made of sheet metal, the walls of which are cleft or slotted as at 58. With this construction the 25 desired resiliency is obtained so that the sole may be flexed in a manner presently to be described without injuring in any way the box-toe of the shoe.

As has been stated, the rollers 13 are 30 spaced apart. In order to provide means whereby a portion of the sole of a shoe may be forced down into the space between these rollers a cross-piece is carried by the arm 45. Any suitable form of cross-piece may be employed, and in the illustrative machine a rod 61 is pinned to the arm 45, said rod being provided with sockets in which are located springs 63 and upon which are rotatably mounted caps 65 in the form of rollers. 35 With this construction the ends of the cross-piece are held at all times in engagement with the sole throughout its entire width, the springs 63 holding the ends of the rollers 65 in engagement with the upper of the 40 shoe.

Actuation of the rollers 13 may be accomplished in any desired manner and, as shown, there are fast to the shafts of the rollers sprocket wheels 67 around which 50 passes a chain 69 which is driven from a large sprocket wheel 71 mounted on a stud shaft 73. The shaft 73 also carries a toothed gear 74 which meshes with a rack 75, said rack being fast to a hand lever 77 which is pivoted to the frame of the machine at 79. In order to permit tightening of the chain 69, the bearings of the outer one of the rollers 13 are carried by a slide 81 which may be moved in and out by means 80 of a screw 83 having a square socket, as shown, to receive a suitable wrench.

The operation of the machine is as follows: The arm 45 is swung out from over the rollers 13 and a shoe is placed upon the 85 shoe support, said shoe occupying the posi-

tion with respect to the support shown in Fig. 2. The arm 45 is then swung back into position shown and pressure is applied to the treadle 19. This causes the cross-piece of the support to force a portion of the sole 70 of the shoe more or less down into the space between the rollers 13 thereby forming an undulation or wave in the sole. The hand lever 17 is then oscillated whereby the rollers 13 are rotated first in one direction and 75 then in the other. This causes the shoe to move forward and back with respect to the shoe support thereby causing the wave or undulation referred to above to travel back and forth along the sole of the shoe. During this operation the toe-piece 57 moves with the shoe so that there is no danger of injury to the box-toe. It should be understood that shoe supports of different sizes 80 may be made use of, if desired, and particularly that interchangeable toe-pieces may be made use of in order to secure proper support for the box-toes of different sized shoes.

Although this machine may be used at any stage in the manufacture of a shoe which 85 may seem desirable, it is particularly effective when made use of subsequent to the leveling operation, since this is the last operation in the manufacture of a shoe which tends to impart stiffness to the sole.

Although the invention has been set forth in connection with a particular machine, it should be understood that the invention is not limited in the scope of its application to the particular machine shown and described. 100

Having thus described my invention, what I claim as new and desire to secure by Letters Patent of the United States is:—

1. A shoe flexing machine having, in combination, means for supporting a shoe, 105 means coöperating therewith for distorting the sole thereof to form an undulation therein, said means comprising members to engage both sides of said undulation, and means for causing said undulation to travel 110 along said sole.

2. A shoe flexing machine having, in combination, a shoe support adapted to engage the inside of a shoe, said support comprising a cross-piece of small diameter, and means for bending succeeding portions of the sole of said shoe successively about said cross-piece.

3. A shoe flexing machine having, in combination, a shoe support comprising a cross-piece, means for bending said sole about said cross-piece, and means for causing relative movement between said sole and cross-piece.

4. A shoe flexing machine having, in combination, two rollers, having a space between them, a roller for pressing a portion of the sole of a lasted shoe into said space, and means for actuating said rollers.

5. A shoe flexing machine having, in combination, two rollers, having a space be- 130

- tween them, a plurality of alined rollers for pressing a portion of the sole of a lasted shoe into said space, and means for actuati-
ng said spaced rollers.
- 5 6. A shoe flexing machine having, in combination, two rollers, having a space be-
tween them, a plurality of alined rollers for pressing a portion of the sole of a shoe into
said space, springs tending to move said
10 alined rollers apart and means for actuati-
ng said spaced rollers.
7. A shoe flexing machine having, in combination, two spaced rollers, a shoe support comprising a cross-piece, said cross-piece
15 being arranged opposite the space between
said rollers, means for causing relative
movement of said support and rollers to di-
minish the distance between them, and
means for actuating said rollers.
- 20 8. A machine of the class described hav-
ing, in combination, a shoe support comprising a yieldingly extensible box-toe sustainer, means for producing in the sole of a shoe mounted upon said support an undulation,
25 and means for moving said shoe lengthwise of the sole thereof, said sustainer following
said shoe in its movements.
9. A machine of the class described hav-
ing, in combination, a shoe support adapted
30 to engage the inside of a shoe, said support comprising an extensible cross-piece of
comparatively small cross-section positioned
at substantially right angles to the longitudi-
nal axis of the sole, and means for bend-
- ing a portion of the sole of a shoe about 35
said cross-piece.
10. A machine of the class described hav-
ing, in combination, a shoe support adapted
to engage the inside of a shoe, said support comprising an extensible cross-piece of com- 40
paratively small cross-section, and means
for bending succeeding portions of the sole
of said shoe successively about said cross-
piece.
11. A machine of the class described hav- 45
ing, in combination, two rollers having a
space between them, a support for a shoe
comprising a cross-piece, said cross-piece be-
ing located opposite said space, means for
causing relative movement between said 50
cross-piece and rollers to press a portion of
the sole of said shoe into the space between
said rollers, and means for moving said
shoe with respect to said rollers.
12. A shoe flexing machine, having, in 55
combination, means for supporting a shoe,
means for forming an undulation in the
sole thereof, and means for producing rela-
tive movement between said sole and said
undulation forming means to cause said un- 60
dulation to travel along said sole.

In testimony whereof I have signed my
name to this specification in the presence of
two subscribing witnesses.
